UNITED STATES PATENT OFFICE.

FANNIE S. SPITZ, OF ALBUQUERQUE, NEW MEXICO.

NUT SHELLING AND SEPARATING MACHINE.

1,211,978.

Specification of Letters Patent.

Patented Jan. 9, 1917.

Application filed September 26, 1916. Serial No. 122,270.

To all whom it may concern:

Be it known that I, FANNIE S. SPITZ, a citizen of the United States of America, and a resident of Albuquerque, county of Bernalillo, State of New Mexico, have invented certain new and useful Improvements in Nut Shelling and Separating Machines, of which the following is a full and clear specification.

13 My invention relates to improvements in nut-shelling machines and has for its object the provision of a machine of this character adapted for removing the hull from piñon and similar nuts.

15 In the drawings Figure 1 is a side elevation of my improved machine, the shelling mechanism being shown partly in section; Fig. 2 is a horizontal sectional view of the stationary shelling member; Fig. 3 is a detail view of the rotary conical shell- 20 ing member; Fig. 4 is a plan view of the separating pan; Fig. 5 is an end elevation showing the front support for the shell- 25 ing mechanism and the blast fan; Fig. 6 is an end view of the rear support for the shell- 30 ing mechanism and the separating pan; Fig. 7 is a plan view of the supporting stand for the shelling and separating mechanism; Fig. 8 is a side elevation of the nut-meat 35 receptacle; Fig. 9 is a plan view of the assembled machine; Fig. 10 is a vertical sectional view of the shelling and separating mechanism; Fig. 11 is a plan view of a slightly modified form of separating pan; 40 and Fig. 12 is a detail plan view of the bearing support for the gearing of the shell- 45 ing and separating mechanism.

My improved apparatus embodies a frame 2, on the top of which is mounted a supporting stand for the shelling and separating mechanism embodying a pair of brackets *s* and *t*, to the top of which is secured a base *j* in the form of an annular ring having a yoke *j*³ extending diametrically across the same, which yoke is provided with a central dome *j*². Mounted upon the base *j* is a stationary shelling member *a* in the form of a hollow cylinder having downwardly and inwardly inclined walls and an outwardly-flared bottom bolted or otherwise secured to the base *j*. The inner surface of the shelling member *a* is provided with vertically-disposed channels *i* extending substantially from the top to the bottom thereof. These channels may, if desired, be made of varying depth for the purpose of securely

holding nuts of different sizes. A hopper *c* is mounted upon the top of the shelling member *a* and is fastened in place by means of wing nuts or other suitable fastening devices. The hopper *c* is provided with a diametrically-extending yoke *d* having a central vertically-disposed shaft-bearing *d*' in which is journaled a vertical shaft *e*. Threaded into the shaft-bearing *d*' is a hollow nut *f* which fits over the top of the vertical shaft and is provided with a plurality of inwardly-projecting lugs or screws *f*' which engage in an annular groove *e*' in the shaft *e*.

At its lower end, the shaft *e* is slidably journaled in a bearing *l*' in bearing-support *l* secured to the base *j* beneath the dome *j*². Near its lower end the shaft *e* is provided with a square portion *e*² on which is mounted a bevel gear *7* having a square opening corresponding to the square portion of the shaft. The bevel gear *7* meshes with the bevel gear *6* mounted on the end of the shaft *5* journaled in the base *j* and the bearing *l*³ of the bearing-support *l*. A hollow conical grinding member *k* is hung on the shaft *e* by means of a screw *g*, so as to rotate therewith and to yield laterally with respect to the shaft when unequal pressure is brought upon its outer surface. The outer surface of the conical grinding member *k* is provided with spiral channels *k*'. Adjacent to its lower end, the conical grinding member is provided with a series of radial passages in each of which is confined a spiral spring *m* bearing upon a ring *m*' loosely mounted on the shaft *e*. The springs *m* are adjustably confined within the radial passages by means of suitable set screws and exert pressure upon the ring *m*' to normally center the cone *k* upon the shaft *e*.

A separating pan *o* is mounted on the supports *s* and *t* beneath the shelling mechanism in a position to receive the cracked nuts delivered therefrom. The pan *o* is provided with a downwardly-inclined and transversely-corrugated bottom *o*'. The lower front end of the pan is supported on the rod *g*' secured in openings *g*² in the front supports *s* by means of one or more brackets *g* riveted at their opposite ends to the bottom of the pan and to lugs *o*' projecting from the front end of the pan. The supports *s* are preferably provided with a plurality of holes *g*² for the purpose of supporting the rod *g*' at different heights to

permit of varying the inclination of the pan σ . The front end of the pan is free to move longitudinally and sidewise on its support. At its rear end, the pan is supported on rod r' by means of suitable straps riveted to the bottom of the pan and is free to move laterally along the grooves or ways r between the supports t . The rod r' is adapted to roll or slide in grooves or ways r formed in the inner faces of the rear supports t . Journaled on a pin 9 depending from the bearing-support l is a bevel gear 8 meshing with the bevel gear 6 . Fixed to the lower face of the bevel gear 8 is a crank pin n , the outer depending end of which is journaled in a hole in the middle of a strap o^3 extending transversely across the pan σ and secured to the side walls of the same. At its lower end, the wall of the pan σ is cut away to form a discharge opening σ^5 for the nut-meats. A blast fan p is mounted on shaft 4 journaled in bracket p' depending from the base j in front of the discharge opening σ^5 , and on the outer end of the shaft 4 is fixed a gear 2 meshing with a gear 1 fixed on the outer end of shaft 5 . The shaft 5 may be driven by a hand-crank as shown in the drawings or by any suitable motor. At its open rear end, the walls of the pan σ are contracted to form a discharge spout σ^2 , the top of which is covered by a hood u secured to the base j . Secured to the discharge end of the spout formed by the contracted portion σ^2 and the hood u is a flexible tubing r supported near its upper end by a bracket 3 attached to the frame z , and this tubing is connected at its lower end to the shell and dust collecting bag supported upon a wire mesh shelf at the bottom of the stand z . A nut-meat receptacle x is supported on the stand z above the shell-collecting bag and is provided at its top with a funnel w disposed beneath the nut-meat discharge opening σ^5 in the supporting pan σ . The receptacle x has an inclined bottom to facilitate the delivery of the nut-meats through the shear-gate y .

In the operation of my device, the nuts fed into the hopper c fall in the space between the stationary grinding member a and the rotary conical grinding member k and are carried downwardly by the action of gravity and the action of the spiral channels on the rotary grinding member. The vertical channels i in the stationary grinding member serve to hold the nuts to facilitate the stripping action of the spiral channels on the rotary grinding member. The space between the outer surface of the conical grinding member and the inner surface of the grinding member may be readily varied by adjusting the nut f in the bearing e' . It will be observed that by loosely hanging the cone k on the shaft c and providing it with a resilient self-centering device, I pro-

vide a delicately adjusted grinding cone which will yield laterally if unequal pressure is brought to bear upon its periphery by the larger nuts, to prevent crushing of the meats thereof. The cracked nuts fall into the separating pan which is given a rotary reciprocatory motion to thoroughly agitate the meats and shells which are at the same time subjected to the action of a blast of air from the fan p passing upwardly and rearwardly along the inclined pan bottom toward the shell and dust discharge spout. The shells and dust are carried by the blast into the collecting sack and the nut-meats are discharged through the opening σ^5 in the front wall of the pan and fall into the nut-meat receptacle x .

If it be desired to separate the whole nut meats from the broken nut meats, I may use the separating device illustrated in Fig. 10. In this device, I attach to the bottom of the pan σ a pan q^3 so that this pan q^3 will be agitated in unison with pan σ . In this pan q^3 I provide a perforated false bottom r^3 , on which bottom the broken meats and the whole meats fall from the pan σ . The vibration of the separating device distributes the meats over the entire area of the perforated bottom and causes the broken and smaller meats to fall through the perforations into a flexible tubing s^3 , while the whole and larger nut meats are carried inwardly and discharged over the inward end of the perforated bottom r^3 , whence they fall into a separate flexible tubing t^3 . The flexible tubes s^3 and t^3 may be connected to any suitable type of separate bin or compartment, preferably of the type shown in Figs. 1 and 8.

Having thus described my invention, what I claim is:

1. In a nut-shelling machine, the combination of a vertically-disposed stationary cylindrical grinding member, a laterally-yieldable conical grinding member rotatably mounted within said stationary member, resilient means for normally centering said conical member vertically within the stationary member, and means for rotating the conical member.

2. In a nut-shelling machine, the combination of a stand, a stationary grinding cylinder mounted thereon, a hopper supported on the top of said grinding cylinder and having a yoke extending diametrically across the top of the cylinder, said yoke being provided with a central vertically-disposed shaft-bearing, a vertical shaft rotatably mounted in said bearing, means for adjustably supporting said shaft embodying a hollow cap threaded on said bearing and having inwardly-projecting lugs engaging in an annular groove in said shaft, a vertically-disposed hollow conical grinding member mounted on said shaft to rotate therewith

and capable of moving laterally with respect thereto, means for normally centering said conical member within the stationary member, and means for driving said shaft.

- 5 3. In a machine of the class set forth, the combination of a stand, and means for separating the meats and shells comprising a pan having a downwardly-inclined bottom and a discharge opening at its lower end and
10 provided with a constricted discharge spout at its upper end, a nut-meat receptacle supported on the stand below the lower discharge opening, a shell and dust-collecting bag supported on said stand and having a

flexible connection with the discharge spout, 15 a fan-blower mounted adjacent the lower discharge opening adapted to deliver an airblast upwardly along the inclined pan bottom toward the discharge spout, means for driving the fan, and means for imparting a 20 rotary reciprocatory motion to the pan.

In testimony whereof I hereunto affix my signature.

FANNIE S. SPITZ.
